UNITED STATES PATENT OFFICE.

LYLE K. SNELL, OF DETROIT, MICHIGAN.

GAUGE.

Application filed September 19, 1923. Serial No. 663,557.

This invention relates to apparatus for indicating pressures and liquid levels and to devices of more general application which may be used in connection therewith.

5 It is one of the objects of the invention to provide a liquid level gauge especially adapted for use on a motor vehicle to indicate the level of the fuel in the fuel tank or the level of the oil in the motor or the 10 level of any other liquid carried by the vehicle.

A further object of the invention is to provide an improved liquid level gauge especially adapted for use on motor vehicles 15 employing the pressure feed system for the fuel; also to provide a gauge for this class of service which will include an indicator for the pressure in the fuel tank.

A further object of the invention is to 20 provide a gauge of the utmost simplicity, one that will have the minimum number of movable parts requiring fixed bearings, and a gauge that will withstand the severe 25 conditions of motor vehicle service without having its accuracy affected.

A further object of the invention is to provide a form of gauge construction that will lend itself readily to modern manufacturing methods for production on a large scale 30 and at a comparatively low cost.

Other objects of the invention are to provide an improved pump in connection with the gauge and to provide an improved form 35 of air valve for use in connection with this pump and for other purposes.

A further object of the invention is to provide a comparatively simple, reliable and effective means for applying my improved gauge to the fuel tanks of motor vehicles 40 now in service.

Other objects of the invention and various 45 illustrations of the features of novelty will be disclosed in the following description taken in connection with the accompanying drawings, in which:

Figure 1 is a side elevation of an automobile having my improved gauge applied thereto, certain parts being broken away;

Fig. 2 is an enlargement of a fragment 50 of Fig. 1 with certain parts shown in section;

Fig. 2^a is an elevation of parts shown in Fig. 2, as seen from the left;

Fig. 2^b is an enlargement of a fragment of Fig. 2;

Fig. 3 is a longitudinal section through 55 the gauge illustrated in Figs. 2 and 2^a; this gauge embodying features of my invention;

Fig. 3^a is an enlarged elevation of one of the parts of the gauge shown in Fig. 3;

Fig. 4 is a transverse section of the gauge 60 on the line 4-4 of Fig. 3;

Fig. 4^a is a fragment of Fig. 4 with a slight modification shown.

Fig. 5 is a longitudinal section on the line 65 5-5 of Fig. 3;

Fig. 6 is an elevation of the gauge as seen from the left of Fig. 5;

Fig. 7 is a detail section on the line 7-7 of Fig. 3;

Fig. 8 is a plan view, with certain parts 70 in section, of the features of my invention associated with the fuel tank;

Fig. 9 is a longitudinal section through a fuel tank embodying my invention, the section being on the line 9-9 of Fig. 8;

Fig. 10 is a longitudinal sectional view 75 through another form of gauge embodying my invention;

Fig. 11 is an elevation thereof, as seen from the left of Fig. 10;

Fig. 12 is a longitudinal section on the line 12-12 of Fig. 10;

Fig. 13 is a transverse section on the line 13-13 of Fig. 10;

Fig. 14 is a view similar to Fig. 2 but 80 showing a different form of pump and also illustrating the form of gauge shown in Fig. 10;

Fig. 15 is an enlarged longitudinal section through the pump illustrated in Fig. 14.

Fig. 16 is a vertical section through a fuel tank embodying a feature of the invention utilized with the gauge illustrated in Fig. 10.

Fig. 17 is a plan view of one of the details 95 shown in Fig. 16;

Fig. 18 is a section through the same prior to its attachment to the tank shown in Fig. 16;

Fig. 19 is a sectional view of a tank and a device for securing thereto the part illustrated in Figs. 17 and 18; and

Fig. 20 is a plan view of one of the parts shown in Fig. 16.

Referring to the drawings and particularly to Fig. 1, I have illustrated, in faint outline an automobile having a fuel tank 30 supported at the rear thereof and the usual dash 31 which carries a hand pump 32 such

as is commonly employed on the Cadillac automobile for supplying pressure to the fuel supply system. One of the pipes of this fuel supply system is illustrated at 33 and as the details of this system form no part of the present invention they have not been illustrated on the drawings and will not be described. It will be understood, however, that the purpose of the pump 32 is to apply pressure to the surface of the fuel in the tank 30 for the purpose of forcing the fuel up to the motor.

My invention is especially adapted for use where it is desired to have a gauge on the dash 31 that will accurately indicate the level or quantity of fuel in the tank 30, and in Fig. 1 I have illustrated a gauge 34 that is connected by small pipes with the tank 30. The specific arrangement of these pipes will be described hereinafter.

Referring now to Figs. 8 and 9 it will be noted that I mount on the top of the tank 30 a fitting 35 that is secured thereto in any suitable manner that will provide an airtight joint connection. There is an opening 36 in the top of the tank and through this opening there projects the stem 37 which is a part of a fitting 38 that is secured on the fitting 35 by screws 39. A gasket 40 may be arranged under the fitting 38 to provide an airtight joint. A pipe 41 of comparatively small bore is secured to the stem 37 and has at its lower end an enlargement 42, the lower end of which is open to the interior of the tank and arranged close to the bottom thereof. As will be noted especially from Fig. 9 the volume of the enlarged member 42 is relatively great as compared with the bore of the pipe 41 and the member 42 is preferably of cylindrical form. The member 42 may be of some other shape than that illustrated but should preferably be of substantially uniform cross section throughout the greater portion of its length for a purpose that will be hereinafter set forth. The fitting 35 has a cylindrical chamber 43 therein which has communication with the interior of the tank 30 by means of a plurality of relatively small holes 44. Within the chamber 43 there are two diaphragms 45 and 46 which are perforated by several small openings, as indicated at 47, with the openings in the diaphragms in staggered relation.

Projecting forwardly from the fitting 35 is an externally threaded extension 48 having an opening 49 therethrough and to which there is attached a short tube 50 having its end flattened, as indicated at 51, to provide a straight narrow opening preferably not over a hundredth of an inch in width. The end 51 of the tube 50 is raised above the diaphragm 46 and the purpose of this arrangement and of the perforated diaphragms 45 and 46, as well as the small perforations 44 in the top of the tank, is to insure against

any of the liquid fuel from getting into the tube 50. The staggering of the openings 47, in the diaphragms 45 and 46, assists in preventing the fuel from getting into the upper part of the chamber 43 in which the tube 50 is arranged.

The fitting 38 has a forward extension 52 of tubular form and provided with a threaded exterior to which the pipe 53 is connected by means of the coupling 54 which is of common construction. A pipe 55 is connected to the extension 48 by a coupling 56 and the pipes 53 and 55 are brought together and secured to one end of the fitting 57, as shown in Fig. 8. A pipe 58 is connected to the opposite end of the fitting 57 and has arranged therein a small tube or pipe 59 which is connected with the pipe 53. The pipe 59 should have a very small bore and I recommend the smallest commercial tubing 85 that can be obtained. By running the tube 59 through the pipe 58 I simplify the work of running these pipes from the fuel tank 30 to the gauge 34 and the pipe 58 serves to protect the pipe 59 against injury due to the external blows from any source.

Referring now to Fig. 2 it will be noted that the pipes 58 and 59 extend to a fitting 60, similar to the fitting 57, the pipe 59 being in communication with a short tube 61 in the same manner that the opposite end is connected with the pipe 53, as shown in Fig. 8. A pipe 62 is also connected with the fitting 60 in the same manner that the tube 55 is connected with the fitting 57, which provides a connection between the tubes 55 and 62 with the interior of the pipe 58. The tube 61 connects with a fitting 63 to which the pipes 64 and 65 are also connected so as to be in communication with the tube 61.

The gauge 34 has two tubular connections 66 and 67 at the back thereof (see Fig. 5) and the pipe 62 is attached to the connection 66 by means of the coupling 68. The pipe 65 is attached to the connection 67 by a coupling similar to 68. The pipe 64 is connected with a valve body 69 by means of the coupling 70 and the valve body 69 is, by preference, attached directly to the discharge connection 71 of the pump 32. The pipe 33 is connected to the valve body 69 by the coupling 72.

The construction of the gauge 34 will now be described and in this connection reference is made to Figs. 3 to 7 in which it will be noted that the housing or shell of the gauge consists of a cylindrical cup having an inturned flange 73 at its open end and provided with an external screw thread 74 for the bezel 75 which secures the glass front 76 to the shell. The periphery of the glass 76 is beveled, as indicated at 77, and the bezel 75 is correspondingly beveled to fit the periphery of the glass and provide an attractive finish as well as to reduce the

distance from the gauge dial to the face of the bezel. A gasket 78 is arranged between the inner surface of the glass 76 and the flange 73 and provides an airtight joint between the glass 76 and the shell of the gauge. A mounting or support 79 for the internal parts of the gauge carries the tubular connections 66 and 67 which project through openings in the end wall of the shell of the gauge. The support 79 is secured in position by means of the nuts 80 and 81 on the tubular connections 66 and 67, a gasket 82 being provided on the interior of the shell for the purpose of making an airtight joint. As shown in Fig. 5 the bore 83 of the tubular connection 66 has communication with the interior of the gauge. The bore 84 of the tubular connection 67 extends through the support 79 and connects with a transverse passage 85 in the support 79, this passage being formed by drilling the support and then closing the outer end of the hole thus formed by means of a plug 86. The support 79 has bosses 87 and 88 on its upper and lower sides, respectively, these bosses being bored and screw threaded to receive the hollow plugs 89 and 90, respectively. The bore of the boss 88 is connected with the passage 85 by a small port 91 which may be formed by drilling. The bore of the boss 87 is connected with a transverse passage 92 in the support 79 by a small port 93. The passage 92 connects with a passage 94 in the support 79 (see Fig. 5) which extends to the rear of the gauge and communicates with the external atmosphere through the aligned ports 95 in the back wall of the shell of the gauge and the gasket 83. The passage 92 may be formed by drilling and the outer end of the hole thus formed may be closed by a plug 96.

A dial 97 is secured to the laterally projecting arms 98 and 99 on the support 79, by the screws 100. The dial 97 is provided with an arcuate offset 101 so that the upper and lower portions of the dial are in different planes.

Referring to Fig. 6 it will be noted that a scale 102 is provided on the upper portion of the dial immediately above the offset 101 and another scale 103 is provided directly beneath the scale 102. I prefer to utilize the scale 102 to indicate the level of the fuel in the tank 30 or the quantity of the fuel in the tank, the two being substantially equivalent. The scale 103 is preferably used to indicate the pressure in the tank 30.

A U-shaped member or yoke 104 is secured to the support 79 by means of the dowels 105 and 106, the ends of the support being recessed, as indicated at 107 and 108 to receive the uprights of the member 104. A lug 109 is pressed out from the member 104 and has a tapered bearing 110 formed therein for one end of a shaft 111, the opposite

end of this shaft being tapered and supported in the adjustable bearing 112 that is carried by the member 104. The shaft 111 has secured thereon a hub 113 on which is mounted the indicating hand 114 which cooperates with the scale 102. The shaft 111 also carries a hub 115 to which the inner end of a spiral hair spring 116 is attached, the opposite end of this spring being secured to the member, as indicated at 117, and the tension in the spring being such as to tend to rotate the shaft 111 in the clockwise direction, as the parts are seen in Fig. 4.

A small bracket 118 (see Figs 3 and 7) is secured to the member 104 by screws 119 and carries one end of a short shaft 120, in the bearing 121, the opposite end of this shaft being mounted in a bearing 122 in the member 104. The shaft 120 carries a hub 123 to which the hand 124 is attached, the latter 85 hand cooperating with the scale 103. The shaft 120 also carries a hub 125 to which the inner end of a spiral hair spring 126 is attached, the outer end of this spring being hooked under the lower edge of the bracket 90 118 in a manner similar to that used in anchoring the spring 116 at the point 117. The spring 126 is so tensioned as to rotate the shaft 120 in the clockwise direction, as seen in Fig. 6.

A hollow diaphragm A, consisting of two circular corrugated discs 127 and 128 having flanged peripheries which are telescoped and sealed in any suitable manner, has its central portion soldered or otherwise affixed to the upper end of the plug 89 (see Fig. 4). The opposite side of this hollow diaphragm has soldered or otherwise secured thereon, at the center, a stud 129, the upper end of

which is bifurcated to receive the lever 130 which is pivotally connected to the stud by the pin 131. One end of the lever 130 is fulcrumed in the opening 132 in the upper end of one arm of the member 104. The opposite end of the lever 130 is provided with

an eye 133 which receives the upper end of a wire or filament 134, the lower portion of which is flattened into the form of a very thin ribbon preferably about 0.0004 of an inch thick. The upper end of this wire may be round and I prefer to make the wire of nickel or phosphor bronze. The flattened part of the wire 134 is wrapped around and secured to the shaft 120, as indicated at 135.

While I prefer to use a metallic wire, flattened as described, for the member 134, yet a thread, of silk or other fibrous material, of a very pliable nature may be employed provided it is substantially inextensible under the tension to which it is subjected in

the gauge.

A hollow diaphragm B, consisting of the corrugated discs 136 and 137, which have flanged peripheries that are telescoped and sealed in any suitable manner, has the center

of the disc 137 soldered or otherwise secured to the plug 90. At the center of the disc 136 there is soldered or otherwise secured a stud 138 which is preferably bifurcated and carries the pin 139. The upper end of a wire or filament 140 is hooked over the pin 139 and this wire is preferably of similar construction to the wire 134, having its lower portion flattened and wrapped around and secured to the shaft 111. (See also Fig. 3^a.)

A perforation at the center of the disc 137 registers with the hole in the plug 90 so that the interior of the diaphragm B is, at all times, in communication with the passage 85 and the bore 84 of the extension 67. This means that the interior of the diaphragm B is in communication with the pipe 59 which has communication, as previously described, with the pipe 53 and with the pipe 41 in the tank 30 and the chamber in the member 42 so that the pressure in the member 42 will be transmitted by the air in the various pipes to the interior of the diaphragm B.

A perforation at the center of the disc 128 registers with a hole in the plug 89 and the interior of the diaphragm A is thereby placed in communication with the passage 92 and, by means of the passage 94, with the external atmosphere so that the interior of the diaphragm A is, at all times, subjected to external atmospheric pressure.

Referring to Figs. 2 and 2^b, it will be observed that the valve body 69 has a bore 141 extending longitudinally of the body, and varying in diameter at different points in its length. At the middle of the valve body there is a chamber 142 which communicates with the bore 141 and this chamber receives the air compressed in the pump 32 by the operation of the plunger 143. The details of the pump 32 are not illustrated because they form no part of the present invention, but any of the air pumps usually employed on automobiles using the pressure system of fuel feed, will answer for the pump 32. At the points 144 the bore 141 is contracted and the tubular valve seats 145 and 146 are secured therein by being forced into position. A valve 147 has a tubular end 148 which is telescoped over the end of the seat 145 but is spaced from the latter to provide an annular passage for air discharged through the seat 145. A disc 149, of rubber or other suitable material, is arranged in the tubular end 148 of the valve and cooperates with the adjacent end of the seat 145 to form a seal and prevent the back flow of air to the chamber 142. The valve 147 has a stem 150 which projects through a plug 151 that is screwed into the valve body and forms a stop for one end of the spring 152, the opposite end of which abuts against a shoulder on the valve 147 to force the latter against the end of the seat member 145. For a pur-

pose to be hereinafter described I make the opening in the plug 151, for the stem 150, only slightly larger than the stem. In the opposite end of the valve body 69 is a valve 153 similar in construction to the valve 147 which has a disc 154 to engage the end of the seat member 146 and prevent back flow of air through the latter into the chamber 142. A plug 155 is screwed into the valve body and forms a stop for one end of the spring 156, the other end of which abuts against a shoulder on the valve 153 and tends to force the latter against the seat member 146. The bore 157 of the plug 155 is considerably larger than the diameter of the stem 158 of the valve 153. When the pump 32 is operated, air, under pressure in the chamber 42, will lift the valves 147 and 153 off their seats and the air will then flow out through the pipes 33 and 64.

In the operation of the gauge above described it is desirable that the chamber in the member 42, as well as the interior of the diaphragm B and the entire length of conduit connecting these two, be maintained at all times substantially filled with air or some other gaseous fluid and, in order to replace any air that may be absorbed by the liquid in the chamber 42 or otherwise lost, I have provided the above described connection between the discharge side of the pump 32 and said conduit so that whenever the pump 32 is actuated to supply pressure to the tank 30 a small amount of air will also be forced into said conduit and any excess over that required to entirely fill the conduit and the chamber of the member 42 and any surplus will escape from the latter into the body of liquid in the tank 30. By providing a very restricted passage through the plug 151 and a relatively large passage through the plug 155 I insure that only a small proportion of the air delivered by the pump 32 will pass into the gauge system and the great bulk of the air will pass into the pressure feed system of which the pipe 33 is a part. I also regulate the distribution of the air discharged by the pump 32 by the tension on the springs 152 and 156, the tension of the latter being preferably more than that of the former.

The novel construction of the valves 147 and 153 whereby the discs 149 and 154 are entirely enclosed by the tubular extensions of the valves, insures against a stoppage, of the relatively restricted passages, by expansion of these discs. Experience with rubber valves in the past has shown that under the action of oil they swell up and such swelling frequently closes the passages through the valve or seriously restricts them. By having the discs 149 and 154 housed in the tubular extensions of the valves there is insurance that any swelling of the discs must take place in an axial direction rather than later-

ally and, therefore, not affect the operation of the valves.

In the operation of the gauge, the pressure in the tank 30 is transmitted to the interior of the shell of the gauge by the pipe system above described so that this pressure acts upon the exterior of the diaphragms A and B. The shell of the gauge is airtight, as previously described, so that the pressure therein is maintained in equilibrium with the pressure in the fuel tank 30. The hydrostatic head of fuel in the tank 30, above the bottom of the member 42, creates a pressure in the chamber of the member 42 as well as on the interior of the diaphragm B which exceeds the pressure of the air in the tank 30 and within the shell of the gauge by an amount equivalent to the hydrostatic head of fuel in the tank. This excess of pressure on the interior of the diaphragm B expands the latter, that is, separates the discs 136 and 137 by an amount dependent entirely upon said excess of pressure. The expansion of the diaphragm B slackens the tension in the wire 140 and the spring 116 rotates the shaft 111 sufficiently to take up the slack in the wire 140. The rotation of the shaft 111 carries the hand 114 to the right, in Fig. 6, to a point on the scale 102 corresponding to the level of the fuel in the tank 30. As the fuel is withdrawn from the tank 30 the hydrostatic head on the member 42 decreases and with it the excess of pressure on the interior of the diaphragm B and hence the latter contracts and, through the wire 140, rotates the hand 114 toward the left so that the latter will at all times accurately indicate the hydrostatic head of fuel in the tank 30. The scale 102 is, of course, calibrated in accordance with the capacity of the tank 30 at the different levels and the calibration of the scale 102 may indicate either the quantity of fuel in the tank or the level of the fuel therein.

Since the interior of the shell of the gauge 34 is subjected to the pressure of the air in the tank 30 it is convenient to combine with the gauge means for indicating the pressure of air and the diaphragm A has been provided for this purpose. Since the pressure in the tank 30 exceeds the atmospheric pressure I open the interior of the diaphragm A to the atmosphere, as above described, and therefore the pressure on the outside of this diaphragm tends to collapse it and depress the free end of the lever 130. This slackens the wire 134 and permits the spring 126 to rotate the shaft 120 and the hand 124 to the right, in Fig. 6, to a point where the hand indicates the pressure on the scale 103. When pressure in the tank 30 is reduced the flexibility in the diaphragm B causes the latter to expand and thus return the hand 124 toward its zero point where the pressure outside the diaphragm is equal to that inside,

In order to prevent injury to the discs forming the diaphragm B, due to excessive expansion, I provide a supporting rib at 159 on the lower side of the support 79 to back up or reinforce the disc 137. I also 70 secure to the support 79 a plate 160, by means of screws 161 and arrange this plate just below the diaphragm B and thereby limit the expansion of the diaphragm.

In Fig. 4^a I have illustrated a modification of the arrangement shown in Fig. 4, to take care of an excessive contraction of the diaphragm B. When the fuel tank 30 is empty the hand 114 will register zero and rest against the stop pin 162 on the dial 97. 75 The pressure will then be equalized on the inside and outside of the diaphragm B and in order to avoid injury to the parts due to further contraction of the diaphragm a spring 163 may be inserted between the upper end of the wire 140 and the pin 139. 80 Under normal conditions the spring 163 is fully contracted and it is not opened except upon an excessive contraction of the diaphragm B. On account of the hand 114 being against the stop 162 such further contraction of the diaphragm would, in the absence of a safety device such as the spring 163, tend to either bend the hand 114 or disarrange some of its operating parts. The 85 same result may be attained by arranging the discs 136 and 137 so that they are in contact whenever the pressure is equalized inside and outside of the diaphragm. With these discs in contact there is, of course, no opportunity for further contraction of the diaphragm.

In practicing my invention it is highly desirable that the amount of air within the diaphragm B and the passages by which this diaphragm is connected with the chamber in the member 42, be as small as practicable in order to avoid errors due to expansion and contraction of this air on account of extreme changes in temperature. It will 110 be apparent that the greater the amount of air in these parts of the apparatus, the more will be the expansion and contraction due to changes in temperature and this contraction and expansion affects the level of the 115 liquid in the chamber of the member 42 or, in other words, affects the pressure in the gauge system due to any given quantity of liquid in the tank 30. The gauge measures the difference in level between the liquid in 120 the chamber of the member 42 and in the tank 30 so that any condition which varies the level in the member 42, from the normal, produces an error in the gauge and, in order to keep this error down to a minimum, it is advisable to use the smallest practicable sizes for the diaphragm B as well as the conduit connecting it with the member 42 and the length of the member 42 should not be greater than that required to prevent the 125 130

liquid from entering the pipe 41 under extreme temperature conditions. The cross sectional area of the chamber in the member 42 should be such that the volume of that part of the chamber in which the liquid is liable to rise is greatly in excess of that of the diaphragm B and the conduit connecting it with said chamber and I would recommend that the ratio of these volumes be not less than 20 to 1.

The volume of the chamber 43 of the fitting 35 is so proportioned relative to the volume of the gauge and the conduit connecting it with the chamber 43 as to prevent fuel from being drawn into the pipes 55 and 58, when the tank 30 is full of fuel, by a shrinkage in the volume of air due to changes in temperature liable to be encountered when the vehicle is suddenly taken from a warm temperature out into below-zero weather, or under other conditions.

The form of the invention illustrated in Figs. 10 to 16 is especially adapted for the so-called vacuum feed system for automobiles. In such systems, which are well-known, the fuel is drawn from the tank at the rear of the vehicle to a small reservoir, near the vehicle motor, by means of suction, the fuel in the tank at the rear being subjected, at all times, to atmospheric pressure.

Referring to Fig. 16 it will be noted that the fuel tank 30 has a member 164 to which there is secured a fitting 165 by means of the screws 166. The fitting 165 carries a pipe 167 which extends into the tank 30 and carries the cylindrical member 42, this arrangement being similar to the form of the invention previously described. A horizontal bore 168 in the member 165 communicates with the pipe 167 and has secured therein a pipe 169 which leads to the gauge on the dash 31 of the vehicle. This gauge consists of a casing or shell 170 having at its front end an inturned flange 171 against which the glass 172 abuts. This glass is secured in position by means of the bezel 173 which has screwed connection with the exterior of the shell 170, as indicated at 174. No effort is made to provide an airtight connection between the glass 172 and the flange 171, as in the form of the invention previously described, since in the present case, the interior of the gauge is subjected to the pressure of the external atmosphere. A mounting or support 175 is arranged within the shell 170 and has an externally threaded extension 176 which projects through the back wall of the shell and whereby the support 175 is firmly secured, a nut 177 on the extension 176 cooperating with the shoulder 178 on the support to clamp the latter to the back wall of the shell.

I have illustrated, as a convenient means for securing the gauge to the dash 31, the U-shaped member 179, the ends of which

abut against the dash, as indicated at 180 and 181, and the middle portion of which is provided with an opening through which the extension 176 projects, a nut 182 on the extension securing the gauge, with the flange 183 of the bezel abutting the face of the dash 31.

The pipe 169 may be connected directly with the extension 176 by means of a common form of coupling such as illustrated at 184 in Fig. 14, but I prefer to connect the pipe 169 with a Y fitting 185 from which the pipes 186 and 187 lead, respectively, to the pump 188 and to the coupling 184.

The support 175 and its extension 176 are provided with an opening 189 with which the pipe 187 communicates. A hollow plug 190 is screwed into a suitable opening therefor in the lower side of the support 175 and to this plug the corrugated disc 191 of the hollow diaphragm C is soldered or otherwise secured. The diaphragm C also comprises the corrugated disc 192 and the discs 191 and 192 have flanged peripheries which are telescoped together and sealed in any suitable manner. An opening 193 in the support 175 places the interior of the diaphragm C in communication with the opening 189, there being a perforation at the center of the disc 191 in registration with the hole in the plug 190. The support 175 carries a circular flange 194 against which the upper surface of the disc 191 abuts.

There is secured to the lower side of the disc 192, at the center thereof, a stud 195 which is bifurcated and carries a pin 196 over which the wire 197 is hooked. The upper portion of this wire may be of circular or other desired cross section but the lower portion is preferably flattened in the same manner as described in connection with the wires 134 and 140 and the end of the flattened portion of the wire is wrapped around and secured to the shaft 198.

The support 175 has a downwardly projecting lug 199 which has a transverse slot 200 and carries two dowels 201. One arm of a bracket 202 is supported on the dowels 201 and the other arm is supported on two dowels 203 and abuts against the front end of the support 175. A dial 204 is secured to the member 202 by means of the screws 205. A lug 206 is punched up from the material of the member 202 and carries one end of the shaft 198 in a conical bearing. The opposite end of this shaft is supported in a conical bearing in the screw 207. The shaft 198 carries a hub member 208 to which the inner end of a spiral hair spring 209 is secured, the outer end of this spring being hooked over the edge of the member 202, as indicated at 210. The shaft 198 also carries a hub member 211 adjacent the dial 204 and this hub member carries an indicating hand 212 which plays over the scale 213 on the

dial. A plate 214 has one end supported in the slot 200 of the lug 199 and the opposite end secured in an opening 215 in the member 202. The plate 214 has a central opening 5 through which the stud 195 projects and is positioned close to the diaphragm C to act as a stop to prevent undue expansion of the diaphragm.

In this form of the gauge the diaphragm 10 C and the conduit pipes and passages connecting the interior thereof with the interior of the member 42, are filled with air so that the hydrostatic head of the fuel in the tank 30, on the air in the chamber of the member 15 42 produces a pressure in the system which expands the diaphragm C an amount corresponding with this hydrostatic head and the expansion of the diaphragm slackens the wire 197 and permits the spring 209 to rotate the shaft 198 in the clockwise direction, as seen in Fig. 11, so that the amount of the expansion of the diaphragm C will be indicated by the position of the hand 212 on the scale 213. The gauge will thus indicate 25 the level or quantity of the fuel in the tank 30, it being understood that the interior of the gauge and of the tank 30 are subjected to atmospheric pressure.

In order to supply air to the system I have 30 provided the Y connection 185 and the pump 188 so that by actuating the plunger 216 of the pump the system may be kept full of air, this being the desired condition.

There are some novel features in the 35 pump 188 and these will be apparent from Fig. 15. The plunger 216 carries a washer 217 and a cup packing 218, the latter being secured by means of a nut 219. The cup packing 218 fits the bore 220 of the pump 40 and the construction just described is well-known. I provide in the end of the plunger 216 a port 221 which communicates with the space between the plunger and the inner wall of the pump, and also with a recess 45 222 in the end of the plunger. A ball valve 223 is arranged in the recess 222 and cooperates with a seat 224 to prevent back flow of air through the passage 221 and into the annular space surrounding the plunger. 50 The nut 219 has an opening 225 which serves as an outlet for the recess 222 so that when the plunger 216 is drawn to the left, as seen in Fig. 15, air will flow through the passage 221, past the valve 223 and through the 55 opening 225 into the pump chamber to the right of the end of the plunger.

On the return stroke of the plunger the ball 223 will prevent back flow and the air will be forced, by the pressure thus created, 60 through the port 226 past the check valve 227 and out into the pipe 186, the latter being connected with the pump by a common form of coupling 228.

There is a bore 229 in the body of the 65 valve 188 and at the inner end of this bore

there is a spherical seat 230 against which the rubber disc 231 is pressed to prevent back flow of air from the bore 229 into the plunger chamber of the pump. The disc 231 is enclosed in a cup-shaped member 70 which prevents lateral expansion of the disc and, therefore, insures against trouble from the swelling of the disc to such an extent as would interfere with the flow of air through the bore 229. The valve 227 has 75 a stem 232 which projects through a plug 233 that is screwed into the pump, there being sufficient space in the plug 233 around the stem 232 to permit the discharge of air therethrough to the pipe 186. A spring 80 234, arranged between the valve 227 and the plug 233, normally presses the valve against its seat 230.

Referring now to Figs. 16 to 19, the fitting 164, as originally constructed, is provided with a tubular extension 235 having a relatively thin wall, the outer end of which has an inturned flange 236. In securing the fitting 164 to the tank 30 I first place the fitting in position on the tank with the extension 235 projecting into the latter, having first inserted the screw 237, which has a head 238 at one end provided with a beveled shoulder 239 to receive the end of the flange 236, as best shown in Fig. 19. A 90 nut 240, on the screw 237, cooperates with the outer surface of the fitting 164 and by turning the nut, and holding the screw 237 against turning, the screw may be drawn through the fitting 164 and, in this operation, the extension 235 will be flattened against the interior of the tank 30, as shown in Fig. 16. The bore of the fitting 164 is just large enough to pass the head 238 of the screw 237 and also to pass the member 95 42. It should also be here stated that the member 42 in the previously described constructions, may be removed from the tank 30 in a similar manner. The manner of attaching the fitting 164, just described, is particularly useful in applying my improved gauge to the tanks of vehicles now in use, as it entirely obviates the necessity for soldering which is dangerous around a tank that has had gasoline in it on account of the 100 liability of an explosion of vapors that may remain in the tank.

While I have shown my gauge in connection with the fuel supply system of a motor vehicle, it will be understood that the invention is equally applicable to other conditions, such as indicating the level of the oil in the crank case and the pressure of the oil being fed to the bearings of a motor, or indicating liquid levels or quantities generally. 110 While I have illustrated what I now consider to be the preferred form of my invention it is realized that the principles involved may be embodied in construction differing in details from those illustrated and 115 120 125 130

I, therefore, claim such constructions as come within the scope of the appended claims.

Having thus described my invention, what I claim is:

1. In apparatus of the class described, the combination of a hollow expansible member, means for subjecting said member to the pressure to be measured, a shaft, indicating means carried by said shaft, a laterally flexible filament having one end connected to said member and its other end connected with said shaft so that the movements of said filament will rotate said shaft in one direction, and means for rotating said shaft in the opposite direction.

2. In apparatus of the class described, the combination of a hollow expansible member, means for subjecting the interior of said member to the pressure to be measured, a shaft, indicating means carried by said shaft, a laterally flexible filament connected at one end with said member and having its other end wrapped around said shaft so as to be able to rotate the latter, means for limiting the expansion of said member, and means for rotating said shaft in opposition to said filament.

3. In apparatus of the class described, the combination of a support, a hollow expansible member secured to said support, there being passages in said support through which communication is established between the interior of said member, a shaft carried by said support, indicating means carried by said shaft, a laterally flexible filament having one end connected to one side of said member and its other end connected to said shaft so as to rotate the latter in one direction, and means for rotating said shaft in opposition to said filament.

4. In apparatus of the class described, the combination of a support having a hollow extension, a hollow expansible member having one side secured to said support, there being passages in said support through which communication is established between the interior of said member and said extension, a shaft carried by said support, indicating means carried by said shaft, a laterally flexible filament having one end connected to one side of said member and its other end connected to said shaft so as to rotate the latter in one direction, means carried by said support on opposite sides of said member to limit the expansion thereof, and means for rotating said shaft in opposition to said filament.

5. In apparatus of the class described, the combination of a support, a hollow expansible member mounted on said support, a conduit having communication with the interior of said member, a shaft carried by said support, a laterally flexible filament having one end connected with said member and the other end wrapped around and se-

cured to said shaft so as to be capable of rotating the latter, indicating means carried by said shaft, and a spring for rotating the said shaft in opposition to said filament.

6. In apparatus of the class described, the combination of a support, a hollow expansible diaphragm comprising two corrugated discs, one of which is provided with means, at its center, connecting it with said support, a conduit extending through said support and communicating with the interior of said diaphragm, a shaft on said support, a filament having one end connected to the central portion of the other of said discs and positioned so as to move endwise with the expansion and contraction of the diaphragm, the other end of said filament being connected with said shaft so as to rotate the latter in one direction, indicating means on said shaft, and a spring for rotating said shaft in opposition to said filament.

7. In apparatus of the class described, the combination of a support, a hollow expansible diaphragm comprising two corrugated discs, one of which is provided with means, at its center, connecting it with said support, a conduit extending through said support and communicating with the interior of said diaphragm, a shaft on said support, a filament having one end connected to the central portion of the other of said discs and positioned so as to move endwise with the expansion and contraction of the diaphragm, the other end of said filament being connected with said shaft so as to rotate the latter in one direction, indicating means on said shaft, means carried by said support on opposite sides of said diaphragm to limit the expansion thereof, and a spring for rotating said shaft in opposition to said filament.

8. In apparatus of the class described, the combination of a support, two hollow expansible members mounted on opposite sides of said support, two independent shafts carried by said support, a dial having a plurality of scales thereon, indicating hands carried by said shafts and cooperating with said scales, two independent laterally flexible filaments each having one end thereof operatively connected with said members, respectively, so as to be movable endwise by the expansion and contraction thereof, the other ends of said filaments being respectively connected with said shafts so as to rotate the latter, and springs cooperating with said shafts to rotate them in opposition to said filaments.

9. In apparatus of the class described, the combination of a shell, a support therein, said shell being substantially airtight, two hollow flexible members mounted on opposite sides of said support, said support having independent passages therein communicating, respectively, with the interiors

of said members, a dial having a plurality of scales thereon, independent shafts carried by said support and provided with indicating hands cooperating with said scales, respectively, a filament having one end connected with one side of one of said members and its other end wrapped around one of said shafts so that the expanding and contracting movements of said member are transmitted to one of said shafts, a spring for rotating said shaft in opposition to said filament, and means for operatively connecting the other of said shafts with the other of said members.
